COLLAPSIBLE WHEEL CHAIR

Edwin Delon and Robert J. Emery, Elyria, Ohio, assignors to The Colson Corporation, Elyria, Ohio, a corporation of Ohio

Application June 2, 1955, Serial No. 512,695

5 Claims. (Cl. 155—147)

This invention relates to improvements in folding or collapsible chairs and more particularly to improvements in vertically folding, preferably wheeled, collapsible chairs and in locking or latching mechanisms for automatically and releasably securing such chairs in the open position.

It is a general object of this invention to provide an improved vertically folding collapsible chair which is attractive and pleasing in appearance, strong and light in construction and easily and readily folded and unfolded, and which may be safely and expeditiously used.

Other objects include the provision of a vertically folding collapsible chair which is substantially automatically and positively secured and locked in the open position when the chair is unfolded, and the provision of an improved locking or latching mechanism for a vertically folding collapsible chair which guides and/or supports the chair seat, which positions the chair when the same is unfolded and locks and secures the chair in the open position, and which is easily and conveniently released or unlocked when the chair is to be collapsed or folded but which will not unlock prematurely or unexpectedly even though the chair frame is twisted, rocked or otherwise distorted.

Other objects include the provision of a vertically folding collapsible wheel chair which may be easily and economically manufactured, which is light, strong and safe, which folds compactly and is easily and conveniently transported, handled and stored as, for example, in an automobile or in the trunk thereof.

Another object is to provide a locking mechanism for maintaining the wheel chair in the open position that is durable, secure and strong, and will not prematurely unlock even though the chair be wheeled when occupied, over rough and uneven surfaces, curbs or other irregularities, or uneven forces are otherwise imposed on the frame, so that the parts thereof are twisted, strained or racked relative to each other.

These and other objects and advantages of my invention will appear from the following description of a preferred embodiment thereof with reference to the appended drawings in which:

Figure 1 is a perspective view of a vertically folding, collapsible wheel chair embodying a preferred form of our invention as shown in its open position.

Figure 2 is a view of the chair shown in Figure 1 when the same is completely collapsed or folded.

Figure 3 is a broken perspective view of the chair looking upwardly at the bottom of the seat and showing the locking mechanism.

Figure 4 is a broken perspective side view of the chair when the same is nearly completely open or unfolded.

Figure 5 is a section taken along the line 5—5 of Figure 3, showing the seat locking mechanism partly in section.

Figure 6 is a top plan view of the seat locking mechanism with the seat removed therefrom.

The preferred embodiment of our invention as shown in the drawings and described below embraces a vertically folding, collapsible wheel chair although certain objects

2

and aspects of our invention are equally applicable to other types of foldable chairs such as those without wheels.

Referring now to Figures 1 and 2, a vertically folding wheel chair 2 embodying a preferred form of our invention has a frame which is conveniently formed from tubular metal. The chair 2 comprises left and right front legs 4 and 6 respectively and left and right rear or back legs 8 and 10 respectively. The respective front and back legs, 10 4 and 8, and 6 and 10 cross each other or intersect X fashion and are pivotally secured together at the point of crossing as by fastening members 12 and 14 respectively. A substantially U-shaped back supporting member 18 and a transversely extending rearward seat supporting member 20 interconnect the upper and rearward ends of the front legs at a convenient height for the seat (when the chair is open or unfolded) and are pivotally secured thereto by pivotal fastening members 22 and 24, Figures 1 and 3.

The lower and forward ends of the front legs are 20 preferably interconnected by a rigid brace or crossbar 25 which is conveniently formed integral with the front legs.

A forward seat supporting crossbar or brace 26, Figure 3, extends between and is secured, as by welding, to the upper forward portions of the rear legs 8 and 10 at such 25 a location as will, when the chair is unfolded, support the forward end of the seat at a proper and convenient height and in proper relation to the height of the rearward seat supporting member 20.

A rigid seat 28 is secured to the rear seat supporting member 20, as by bolts and nuts 32, for pivotal motion about the pins 22—24, and extends forwardly of and rests upon and is supported by the forward crossbar 26. A locking or latching mechanism indicated generally at 34 and hereinafter more fully described, releasably secures the seat 28 to the forward seat supporting crossbar 26 when the chair is unfolded to its open operative position as shown in Figure 1.

The rear legs 8 and 10 are bent upwardly and inclined rearwardly just forward of the cross bar 26 as at 38 and 40 respectively to form the front posts 42 and 44. The posts 42 and 44 are of sufficient length to support the left and right arm rests 46 and 48 at a convenient height when the chair is unfolded. The left and right arm rests 46 and 48 extend between the front posts 42 and 44 and the back supporting member 18 and are pivotally secured to the front posts 42 and 44 respectively and the back supporting member 18 by pivotal fastening members 50 and 52 and 54 and 56 respectively.

The lower and rearward ends of the back legs 8 and 50 10 are preferably provided with transversely extending holes through which an axle 62 extends. Left and right wheels, 64 and 66 respectively, are mounted on the axle 62 as shown.

The front legs 4 and 6 are preferably bent forwardly 55 near their forward and lower ends as at 70 and 72 respectively so as to extend substantially parallel with the floor, and castor type front wheels 74 and 75 are secured to these forward portions thereof. The relationship between the size of the front wheels 74 and 75 and the angle and location of the bends 70 and 72 is such that when the chair is folded the front wheels will extend angularly forwardly (see Fig. 2) relative to the rear axle so that the forward end of the chair when folded will not be substantially higher than the diameter of the rear wheels and the folded chair will be compact in size and therefore easily handled, transported and stored.

A rigid back 76 is secured to the back supporting member 18, and a footrest 78 is pivotally secured to the lower forward portions of the front legs. The footrest is supported by brace 25 when in position for use as shown in dotted lines in Figure 1, but may be turned up and back

to facilitate the compact folding of the chair, Figures 1 and 2.

The locking mechanism indicated generally at 34, Figures 3 and 4 is adapted to automatically secure, position and lock the chair in the open, unfolded operative condition, and to support and guide the seat at all other times. As will hereinafter more fully appear, the locking mechanism is adapted on the one hand to safely and securely lock the chair in the open or unfolded position and preclude the premature or undesired collapsing thereof even though the chair be lifted by the seat, pushed or wheeled over rough and uneven surfaces, curbs and steps and the frame be thereby unevenly loaded, twisted and racked and on the other hand to be easily and conveniently unlocked whenever it is desired to collapse and fold the chair.

The locking mechanism, see Figures 3, 4, 5 and 6, includes a downwardly opening channel member 82, which extends transversely of and is secured to the forward under side of the seat 28 (as suggested by bolts 28a having minimum protuberance above the top surface of the seat and within the channel) and is adapted to fit over and seat upon the forward seat brace 26 when the chair is fully and properly opened, means to automatically position the channel 82 as the chair is opened and means to releasably lock the channel in seated engagement with and over the brace 26.

To this end the channel 82 preferably and conveniently has a depth greater than one half the diameter of brace 26 and a width between its front leg 84 and rear leg 86 which is only slightly larger than the diameter of the brace and a length about equal to one half the width of the seat 28. Thus when the chair is opened and the channel is seated on and over the seat bar the engagement therebetween is such as to preclude the premature or unwanted raising of the seat relative to the brace 26 or release of the locking mechanism or disengagement of the channel and seat bar and/or inadvertent collapsing or folding of the chair.

In order to position the chair and seat properly and to prevent the channel 82 from being carried forwardly of the brace 26 when the chair is unfolded a flat hook or stop member 90 is secured, as by welding, to the rearward side of the rear leg 86 of channel 82. The stop 90 extends, preferably in an arc, downwardly and forwardly from the leg 86 so that its lower edge 94 lies below and forwardly of the leg 86. The stop is of any convenient width and thickness and of sufficient length to catch and bear upon the brace 26 as will hereinafter more fully appear.

A resilient locking bar 98 is secured, near its right end as viewed in Figure 6, to the forward leg 84 of the channel 82. The locking bar 98 lies parallel with and extends longitudinally along the channel leg and has its left end 100, as viewed in Figure 6, which extends beyond the end of the channel towards the side of the chair, Figures 3 and 6. The locking bar is secured to the channel leg 84 near its right end by a pair of longitudinally spaced nuts and bolts or rivets 96. The outer portion 100 of the bar conveniently extends almost to the outer edge of the seat 28 and is preferably bent slightly forward so that the user may, when desired or necessary, easily grasp it and pull the left end of the bar forwardly against its own resilience wherewith to "unlock" the channel from the brace, as will more fully appear.

A flat curved guide member 108 is secured as by welding to the upper portion of the brace 26, Figures 3, 5 and 6, and extends forwardly slightly beyond the brace and rearwardly and downwardly behind the brace for a distance exceeding the relative rearward and downward motion of the channel relative to the brace when the chair is entirely folded. The guide member 108 is adapted to guide the movement of the seat 28 and support the seat and channel 82 when the chair is being unfolded or folded or is in the folded position. To this end the

member 108 is secured to the brace 26 at a point nearer the side of the chair than the adjacent end of the channel 82 and toward the same side of the chair to which the end 100 of the locking bar 98 extends. More particularly 5 the seat and channel are supported by the locking bar riding on and supported by the upper side of the guide 108 when the chair is in other than the fully open position, see Figure 4. The guide 108 extends over and forwardly from the brace 26 a distance sufficient to raise the locking bar 98 and the forward leg 84 of the channel 82 above and over the brace 26, when the chair is being opened, but a distance insufficient to raise stop 90—92 over the brace. Thus the forward movement of the seat is arrested 10 when the stop 90 engages the brace 26 and the channel 15 is then positioned above the brace so that a downward movement of the seat brings the channel down to straddle and engage the brace, Figure 5. Meanwhile the sprung end 100 of the locking bar 98 has rested on the forwardly and downwardly sloping surface of the guide 108 whence forcible downward movement of the seat and channel 20 springs the end 100 of the locking bar over the end of the guide, permitting the channel to come down on the brace, and the position of the end 100 of the guide is related to the upper edge of the locking bar such that the bar springs 25 back under the end of the guide when the channel is "home" and seated on the brace, Figure 5. Thus the seat is locked and secured in the open position and cannot be removed therefrom until the end 100 of the locking bar is sprung outwardly as suggested in dotted lines at 100a in 30 Figure 6.

The guide member 108 also extends rearwardly and downwardly from the brace 26 and is of sufficient length to support the locking bar when the chair is completely folded. The angle at which the guide 108 extends is 35 conveniently such as to support the seat in the position shown in Figure 2 when the chair is folded. Since the seat is supported on the guide 108 by the bar 98 when the chair is folded and since the guide is secured to the upper part of the brace 26, the seat will always be raised above 40 the seat bar 26 when the chair is unfolded and will not be caught beneath the seat bar as might otherwise be possible.

In operation and with the chair folded as shown in Figure 2, the seat will, as previously explained, be supported in the position shown by means of the locking bar 98 resting upon the upper side of the guide member 108. To unfold the chair, the user need merely grasp the horizontal portion 114 of the back supporting member 18 and raise up on the same. This in effect causes the front part 50 of the seat to move in a forwardly and upwardly direction, the front wheels to move in a rearward direction, and the brace 26 to move in and upwardly and rearwardly direction relative to the seat and channel. Thus the motion of the chair seat is forward and that of the brace 55 rearward and their relative motion is toward each other. As the chair unfolds the locking bar 98 rests on and rides upon the guide 108 and when the chair approaches its opened position the bar 98 will have ridden up the guide to the highest point thereof thereby lifting the channel 60 82 up and over the brace 26 and continued opening of the chair is indicated by the stop 90 catching against the brace and preventing any further forward movement of the seat and channel relative to the brace. The seat 28 is then moved downwardly by pressure exerted thereon by 65 the user. The downward movement of the seat causes the locking bar 98 to move downwardly and forwardly on and over the upper and forward sloping side of the forward portion 110 of the guide 108 and as the bar moves downwardly thereon it is simultaneously displaced forwardly against its resilient resistance so as to move downward in front of the forward end 110 of the guide. Simultaneously the channel 82 is moved downwardly over the brace 26. Continued downward movement of the seat causes the channel to seat upon and over the brace and moves the 70 top of the locking bar below the lower edge of the end 75

110 of the guide, thereby catching the locking bar beneath the forward end of the guide and securely locking the chair in the open position.

When it is desired to fold the chair, the end 100 of the locking bar 98 is pulled forwardly of the end 110 of the guide and the seat is raised upwardly until the channel is disengaged from the brace 26. The locking bar is released and the chair tends to collapse and/or may be folded from the position of Figure 1 to the position of Figure 2 (or is permitted to fold slowly), the locking bar riding upon the guide 108 and supporting the seat during and after completion of the folding as hereinbefore described.

Preferably the arms and legs of the chair are so proportioned that the pivot points 54 and 565 may be gently forced slightly beyond "center," i. e., beyond lines joining the points 24—52 and 22—50 respectively when the chair is fully folded, giving the chair a tendency to stay folded in the position shown in Figure 2 until a mild but measurable opening force is exerted thereupon. Resilient contact between the bar 98 and the guide 108 remote from the brace 26 when the chair is in its folded position, Figure 2, tends to stress and hold the chair in its "over-center" folded position.

While we have illustrated and described a preferred form and embodiment of our invention, changes, modifications and improvements thereto will occur to those skilled in the art and therefore we do not desire to be limited in the scope of our patent to the specific and illustrative disclosure hereof nor in any manner inconsistent with the progress by which our invention has promoted the art.

We claim:

1. In a foldable chair adapted for vertical folding motion comprising left and right front and rear legs, each said front leg being pivotally connected to an adjacent rear leg at a point remote from their respective ends, a seat pivotally secured to and interconnecting said front legs above said pivotal connections with said rear legs, a seat bar or brace secured to and interconnecting said rear legs above said pivotal connections with said front legs and adapted to support said seat when said chair is unfolded, and having a locking mechanism for releasably securing said chair in the unfolded position and guiding said seat during the folding and unfolding of said chair, the improvement wherein said locking mechanism comprises a downwardly opening channel having front and rear legs secured to the forward under side of said seat and extending transversely thereof and having a length less than the width of said seat and being adapted to engage said seat bar, a stop member secured to the rear leg of said channel and extending downwardly and forwardly therefrom, a locking bar secured to the front leg of said channel and extending parallel therewith and extending nearer one edge of said seat than the adjacent end of said channel, means resiliently urging said locking bar against the front leg of said channel, and a guide member secured to the upper and rearward portion of said seat bar between the end of the locking bar and the adjacent end of the channel, said guide bar having a rearward por-

tion extending downwardly and rearwardly from said seat bar and a forward portion extending downwardly and forwardly from said seat bar, said guide member being adapted to support and guide said locking bar while said chair is being folded and unfolded and to retain said locking bar when said channel is seated over said seat bar.

2. In a foldable chair adapted for vertical folding motion comprising left and right front and rear legs, each said front leg being pivotally connected to the adjacent rear leg at a point remote from their respective ends, a seat adapted to pivot about an axis between the upper ends of said front legs above said pivotal connections with said front legs, a brace interconnecting said rear legs and adapted to support said seat when said chair is in the unfolded position, and having a locking mechanism for releasably securing said chair in the open position and guiding said seat during the folding and unfolding of said chair, the improvement wherein said locking mechanism comprises means secured to the forward under side of said seat and adapted to engage said brace, stop means adapted to limit the forward travel of said means relative to said brace when said chair is unfolded; guide means for supporting and guiding said seat when said chair is folded and being unfolded, and locking means for releasably securing said means for engaging said brace in engagement with said brace when said chair is completely unfolded.

3. The chair locking mechanism according to claim 2 in which said brace engagement means comprises a downwardly opening channel extending transversely of said seat.

4. The chair locking mechanism according to claim 2 in which said locking means includes catch means secured to said brace and latch means carried by said seat and adapted to releasably engage said catch when said chair is secured in the open position and to slidably engage said guide means and support said seat when said chair is being folded and unfolded.

5. Locking mechanism for a folding chair having a seat and a cross bar in which a connection between the seat and a cross bar retains the chair in open position and folding the chair involves rearward sliding motion between the seat and the cross bar, said mechanism comprising a U-shaped member carried by the seat and receptive of the cross bar when the chair is in open position, a guide element spaced from the U-shaped element and overlying the bar and extending downwardly, rearwardly and forwardly therefrom, and a resilient locking bar having an end fixedly associated with the seat remote from said guide element and adapted to ride on said guide element and snap over and be caught under the forward end of said guide element when said cross bar enters said U-shaped element.
